UNITED STATES PATENT OFFICE.

THOMAS ALLSOP AND WALTER W. SIBSON, OF PHILADELPHIA, PENNSYLVANIA,
ASSIGNORS TO THE PHILADELPHIA DRYING MACHINERY COMPANY, OF GER-
MANTOWN, PHILADELPHIA, PENNSYLVANIA, A CORPORATION OF PENNSYL-
VANIA.

DRYING AND CONDITIONING MACHINE.

1,304,645.

Specification of Letters Patent.

Patented May 27, 1919.

Application filed February 19, 1919. Serial No. 278,087.

To all whom it may concern:

Be it known that we, THOMAS ALLSOP and WALTER W. SIBSON, citizens of the United States, residing in the city and county of Philadelphia and State of Pennsylvania, have invented certain new and useful Improvements in Drying and Conditioning Machines, whereof the following is a specification, reference being had to the accompanying drawings.

The invention relates to machines employed in treating materials such as yarn, etc., to place them in the proper condition for use in the course of being manufactured into textile fabrics. Such requirements not only necessitate the ordinary drying operation, for example, after dyeing or bleaching, but the materials must also be conditioned in order to absorb the requisite amount of moisture to render them sufficiently pliable in running through the various stages of manufacture.

In attaining this objective, the machine constructed according to our invention embodies in a unitary structure, a chamber which may be employed alternatively either for drying or cooling, according to particular requirements, and a second chamber for the conditioning of the materials, or the one may be employed for drying only, and the other for cooling and conditioning.

Our invention also comprehends means whereby the outside atmosphere may be employed in effecting the cooling operation, and also means for re-circulation of a proportionate amount of the fresh air during passage through the machine.

In the accompanying drawings, Figure I, is a front elevation of a drying and conditioning machine conveniently illustrating our invention.

Fig. II, is an end elevation of the same as viewed from the right of Fig. I, and

Fig. III, is a central longitudinal section through the machine.

As herein shown, the invention consists of an inclosure 1, having a structural steel skeleton which serves to support the inclosing walls which are preferably formed of panels 2, of sheet metal, having interposed layers of thermo-insulating material such as asbestos or the like. These are of well-known fire proof construction and may be

attached in any convenient manner. As shown in Fig. III, of the drawings, the 55 inclosure 1, is laterally divided by a central partition 3, into two compartments respectively indicated by the numerals 4, and 5. Said compartments are partly bounded by sloping roof portions 6—6, inclined downwardly toward the central partition 3, in symmetrical relation thereto. While the partition 3, is illustrated only conventionally herein, in actual practice it is so constructed as to be thermo-insulating, whereby cross radiation between the chambers 4, and 5, is absolutely prevented.

The two sections may be employed for different purposes, but for choice of illustration, the one at the left, indicated at 4, 70 has been arranged as a drying or cooling compartment, while the one at the right, designated at 5, has been designed to serve as a conditioning compartment.

A transverse vertical partition 7, subdivides compartment 4, thereby affording in addition to a main chamber 8, a smaller auxiliary chamber 9. The main chamber is of ample proportions to receive trucks or other apparatus supporting the materials to be treated and to this end has been provided, as shown in Fig. I, with doors 10—10. The smaller chamber 9, may be employed for the accommodation of any adjunctive devices such as heating coils 11, 85 which may or may not be employed, depending entirely upon the treatment desired. Chamber 9, also serves under certain conditions as a by-pass, functional in shunting a portion of the air in the compartment for recirculation in a manner to be described later.

Near its top, and in line with the longitudinal center of the machine, the partition 7, is provided with a circular opening 12, 95 for the reception of a fan 13. Inter-communication between chamber 8, and 9, is also established through an opening 14, at the bottom of partition 7, so that the motion of the fan will cause a certain amount 100 of the air in the compartment to be re-circulated as indicated partially by the arrows in Fig. III. In order to vary the extent of this re-circulation the chamber 9, has been interrupted by a horizontal diaphragm 15, having an opening 16, governed

by a damper 17. This damper is hinged at 18, and is adjustable from without the enclosure by means of a chain or cord 19, passing over a pulley 20. After the desired 5 adjustment has been obtained, the chain 19, may be detachably secured upon the exterior of the machine by any convenient means.

A conduit 21, communicating with the 10 outside air enters the chamber 8, at the top, and a discharge conduit 23, leads from the latter at the bottom. These conduits are respectively provided with controlling dampers 22, and 24. The continuous rotation 15 of the fan 13, causes the cool air to be sucked into the chamber 8, through the conduit 21, under control of damper 22, so that in addition to the re-circulation already described, a proportionate amount of fresh 20 air is constantly admitted and the displaced portion exhausted through the discharge conduit 23. By the relative adjustment of dampers 22, and 24, these proportions may be varied in accordance with the most 25 acting requirements of each of the different materials treated. Exterior communication may be completely shut off by closing the dampers 22, and 24, in the event of which the air entrapped in the chamber would be 30 constantly re-circulated, but in the illustration of Fig. III, these dampers are slightly open, and the arrows indicate the complex air circuits under these conditions.

In a manner similar to that previously 35 described in connection with compartment 4, the conditioning compartment 5, is also subdivided by a partition 25, to afford in connection with a main chamber 28, a smaller auxiliary chamber 29, in this instance for 40 the accommodation of a heating coil 30, and a humidifying apparatus comprehensively indicated at 31. The larger chamber 28, is of the same size as the chamber 8, for the accommodation of trucks loaded with the 45 material for treatment and is similarly provided with doors 32—32. See Fig. I. Circulation in this compartment of the machine is effected by means of a fan 33, centrally located in an opening 34, at the top 50 of partition 25, and intercommunication between the two chambers established through an opening 35, at the bottom of said partition.

The heating means consists of a coil or 55 coils 30, of pipe entering at 36, in Fig. II, and leaving at 37. The temperature in the compartment is maintained at the proper predetermined degree through the instrumentality of a thermostat diagrammatically 60 represented at 38, and connected through any convenient leverage system with a controlling valve 39, in the heating pipe 30. The humidifying apparatus 31, may be of any well-known construction. As herein shown it comprises a series of atomizing noz-

zles 40, preferably grouped for symmetrical distribution in the chamber 29. These nozzles are supplied with steam or air and water through the pipes 41, and 42, having hand controlling valves 43, and 44, respectively. Flash plates 45, 45, coöperate with nozzles 40, in facilitating atomization. By the proper relative adjustment of these valves, any desired condition of humidification may be obtained, depending entirely 75 upon the requirements of the goods under treatment.

Compartment 5, is also provided with an exhaust conduit 50, communicating with the outside atmosphere. This conduit 50, is controlled by a damper 51, which may be adjusted to permit a proportionate discharge 80 of the humidified air from the compartment 5, as indicated by the arrows.

The circulating fans 13, and 33, are 85 mounted upon a common driving shaft 52, having the usual tight and loose pulleys 53, and 54. This shaft is journaled at its ends in bearings 55, and 56, fixed to vertical T-bars 57 (see Fig. III), comprised by the 90 structural framework of the machine, and at the center in a bearing 58. Said bearing is located in the interspace between the sloping roof portions 6, and mounted in a channel 59, extending transversely of the machine above the central partition 2. This channel is also a part of the structural skeleton and as shown in Figs. I, and II, is supported by the longitudinal angle bars 60. It will be noted from the direction of the 95 circuits indicated by the arrows in Fig. III, that the actions of the fans are in direct opposition, so that the corresponding components of the longitudinal thrust upon the shaft will neutralize each other and as a 100 consequence perfect equilibrium established.

The chambers 8, and 28, are further provided with slotted protective diaphragms or sub-ceilings 65, and 66, respectively. These are functional in preventing the goods under treatment from being drawn into the fans and also serve to subdivide the air currents during circulation.

In actual practice, the machine constructed according to our invention lends itself 115 readily to various modifications in the methods of the treatment of the materials. For example, if it be desired first to dry the materials subsequent to bleaching or dyeing, the truck is run into chamber 8, the 120 dampers 22, and 24, regulated to the desired extent, and steam, to the coils turned on. The constant re-circulation of the heated air will, in this event, serve to effectively dry the materials in being forced through the 125 same. After the drying treatment has been completed, in order to change the temperature of the materials to the proper degree for conditioning, it is necessary to subject the same to a cooling treatment which is 130

effected by simply shutting off the steam supply to coils and opening the dampers 22, and 24, and thereby permit the influx of external air under the action of the fan 13, 5 with provisions for a certain amount of re-circulation under control of damper 17, and exhaust damper 24, as already explained. After the material is cooled to the required degree, the truck is withdrawn 10 from chamber 8, and run into chamber 28, for conditioning, the re-circulation of the humidified air causing thorough penetration in accomplishing the desired end.

In the treatment of certain classes of 15 goods, the drying operation may be entirely dispensed with, thereby obviating the necessity of the heating coil 11, and the process begun with the cooling and subsequently completed by the conditioning operation.

20 It will thus be seen that our invention may be adapted to various uses and we, therefore, do not wish to limit ourselves to the precise details of construction and arrangement herein shown, since various 25 modifications may be made therein without departing from the spirit thereof.

Having thus described our invention, we claim:

1. A machine of the class described comprising, in a unitary structure, a drying and 30 cooling compartment, and a conditioning compartment; a separating partition subdividing each of said compartments into a main chamber and an auxiliary chamber; 35 means located in each compartment for circulating the air between the said main and auxiliary chambers; and means for permitting the exhaust of a proportionate amount of the air circulated in each of said 40 compartments.

2. A machine of the class described comprising, in a unitary structure, a drying and 45 cooling compartment, and a conditioning compartment; a separating partition subdividing each of said compartments into a main chamber and an auxiliary chamber; means located in each compartment for circulating the air between the said main and auxiliary chambers; a valved fresh air 50 conduit leading to the said heating and cooling compartment; a valved exhaust conduit leading from the said drying and cooling compartment; and means for controlling the re-circulation of a proportionate amount of 55 the fresh air drawn into said compartment.

3. A machine of the class described comprising, in a unitary structure, a drying and 60 cooling compartment, and a conditioning compartment; a separating partition subdividing each of said compartments into a main chamber and an auxiliary chamber; means located in each compartment for cir-

culating the air between the said main and auxiliary chambers; a valved fresh air conduit leading to the said heating and cooling 65 compartment; a valved exhaust conduit leading from the said drying and cooling compartment; a diaphragm interrupting the auxiliary chamber of the drying and cooling compartment; an adjustable damper controlling an opening in said diaphragm, whereby a proportionate amount of the 70 fresh air drawn into said drying and cooling compartment may be re-circulated.

4. A machine of the class described comprising, in a unitary structure, a drying and cooling compartment, and a conditioning compartment; a separating partition subdividing each of said compartments into a main chamber and an auxiliary chamber; 80 means located in each compartment for circulating the air between the said main and auxiliary chambers; heating coils located in the auxiliary chamber of the drying and cooling compartment; heating and humidifying means located in the auxiliary chamber of the conditioning compartment.

5. A machine of the class described comprising, in a unitary structure, a drying and 85 cooling compartment, and a conditioning 90 compartment; a separating partition subdividing each of said compartments into a main chamber and an auxiliary chamber; means located in each compartment for circulating the air between the said main and auxiliary chambers; heating coils located in the auxiliary chamber of the drying and cooling compartment; heating and humidifying means located in the auxiliary chamber of the conditioning compartment; and 95 thermostatic means for controlling the temperature in the said conditioning compartment.

6. A machine of the class described, comprising, in a unitary structure, a drying and 100 cooling compartment, and a conditioning 105 compartment, a separating partition subdividing each of said compartments into a main chamber and an auxiliary chamber, rotary fans located in said partitions, and 110 adapted to circulate the air between the respective main and auxiliary chambers; and slotted protective diaphragms spanning said main chambers in proximity to said rotary fans.

In testimony whereof we have hereunto set our hands at Philadelphia, Pennsylvania, this fourth day of February 1918.
